CONTAINER CLOSURE

Malcolm S. MacGruer, Greenwich, Conn.

Application March 24, 1959, Serial No. 55,143

Term of patent 14 years

(Cl. D58—10)

FIG. 1

FIG. 2

The dominant features of my new design are shown in solid lines. The side not shown is identical in appearance to the side illustrated. The back side of the article is a continuation of the surface at the left side of Figure 2 and is free of ornamentation.

I claim:

The ornamental design for a container closure, as shown and described.
